UNITED STATES PATENT OFFICE.

PETER P. WELTY, OF PANDORA, OHIO.

CORNER PIECE FOR BUILDING STRIPS.

Application filed June 17, 1925. Serial No. 37,736.

To all whom it may concern:

Be it known that I, PETER P. WELTY, a citizen of the United States, residing at Pandora, in the county of Putnam and State of Ohio, have invented new and useful Improvements in Corner Pieces for Building Strips, of which the following is a specification.

This invention relates to siding strips for building purposes composed of flexible, water-proof material adapted to be laid in overlapped courses and each strip constituting a member of the covering of the side of a building, and the present improvement has particular reference to a novel form of combined inner and outer corner piece or strip. The present invention is an improvement on the siding strips and corner pieces disclosed by my Patent No. 1,515,530, dated 20 Nov. 11, 1924.

The primary object of the present invention is to provide an inner and outer corner strip in one structure instead of using two separate strips or pieces as in my above noted patent, and to render the single corner strip having the dual function specified readily applicable to inner and outer corners by simply reversing the strip, and thus materially economize in building structures 30 having siding strips cut to simulate bricks and laid in overlapped relation or courses.

A further object of the present invention is to expedite the application and corner completion of siding structures embodying 35 overlapped strips of flexible material cut to simulate bricks or the like, and to form a finished corner jointure in such manner that a stronger and more durable siding is provided with a neater appearance.

With the foregoing and other objects and advantages in view, the invention consists in the construction and arrangement of the several parts which will be more fully hereinafter described and claimed.

In the drawings:

Fig. 1 is a perspective view of portions of the sides of a house with cut flexible strips applied thereto and overlapped to simulate courses of brick and showing the 50 improved unitary angle piece applied to the inner angle.

Fig. 2 is a view similar to Fig. 1, showing the improved angle piece applied to the outer angle.

Fig. 3 is a detail elevation of the improved unitary angle piece or strip shown

in position for application to an inner angle.

Fig. 4 is a view similar to Fig. 3, showing the improved unitary angle piece or strip arranged for application to an outer angle. 60

The numeral 5 designates a plurality of building strips, which may be made in any suitable length and thickness, and extending a predetermined distance inwardly from one side edge of each strip are a plurality of 65 regularly spaced slots 6, all of the slots being of equal length. This strip 5 with the slotted edge may be made in very long lengths and rolled, the strip being rendered more efficient in its strength and durability 70 by suitably treating the same with asphalt or an asphalt solution, or any water-proofing and preservative medium. The improved strip may be primarily formed of paper stock of suitable thickness or any 75 other analogous flexible material of a comparatively cheap character and strengthened and rendered water-proof by treatment as above noted, and when the lengths of the improved strip are completed, they may be 80 conveniently applied to various portions of the sides of a house or building. The strips are cut the desired lengths when they are applied, and at the inner and outer angles supplemental corner pieces or strips are 85 provided and are shown in detail by Figs. 3 and 4, a single or unitary strip being used in this instance for both the inner and outer corners and generally designated by the numeral 7. The corner piece or strip 7 is 90 substantially rectangular in its contour, or is longer than it is wide, and the upper edge is formed with two inclines 8 extending downwardly from a central maximum projection 9 to the opposite side edges of the 95 piece or strip. The lower edge of the piece or strip has upwardly inclined portions 10 intersecting at a maximum depression 11, the inclines 10 also extending downwardly and intersecting the side edges of the piece 100 or strip. The opposite end edges of the piece or strip 7 are formed with central rectangular projections 12 and the end edge portion 13 below each projection extends at a slight inward angle from the lower side edge of the piece or strip, and the upper edge portion 14 extends outwardly at a slight inclination to the upper edge of the said piece or strip, both edge portions 13 and 14 at opposite ends of the strip being similar in 105 construction and angular arrangement. The end edges of the piece or strip as just speci-

110

fied meet the upper and lower side edges of the piece or strip in angular corner formations, as at 15. The maximum projection of the upper edge of the piece or strip 7 is in vertical alinement with the maximum depression 11 of the opposite lower side edge, and in applying the improved unitary corner piece or strip, the same is bent inwardly centrally in a vertical plane or outwardly 10 in accordance with the application thereof to an inner or outer corner.

The centrally disposed end projections 12 contribute to the formation of half slots at opposite ends of the improved piece or strip 7, so that when the latter is applied either at an inner corner or an outer corner, these half slots complete the full slots of the strips 5 which are cut to terminate at a distance from the corner either at an inner or outer 20 angle, as clearly shown by Figs. 1 and 2, and when the pieces or strips 7 are applied and the overlap of succeeding elongated strips 5 is formed, the upper portions of the said pieces or strips 7 are covered, as is 25 also shown by Figs. 1 and 2. It will be understood that the pieces or strips 7 in addition to their particular adaptation to inner and outer corners of the intersecting sides or sides and ends of a building also serve as 30 filling pieces and give the strips 5 that may be cut at the corners a continuous appearance, and further, provide a convenient means for accurately filling in the spaces between the terminating extremities of the strips 5 at the corners without requiring a 35 preparation of parts of the strips 5 for the same purpose. When the improved piece or strip 7 is applied to the inner corner, the same is centrally bent with the maximum 40 projection 9 at the top, and owing to the bend the inclined edge portions 8 and 10 aline with the corresponding upper and lower edges of the strips with which the corner pieces are directly associated. When 45 the corner piece is applied to an outer corner, it is reversed; so that the depression 11 is uppermost and also the adjacent inclined edge portions 10, the latter edge portions extending upwardly from the depression and 50 assuming a proper position when the piece as shown by Fig. 4 is centrally bent and applied to an outer corner as particularly illustrated by Fig. 2. In all the applications of the improved corner piece or strip as hereinbefore specified, the same is uniformly 55 centrally bent or folded with the maximum projection 9 at the center of one edge and the maximum depression 11 at the center of the opposite edge as the alined guiding means for forming the bend.

As specified in my patent hereinbefore noted, the strips 5 are given a maximum overlapped arrangement against the side of a building and they will thus be less liable 65 to become loose and bend upwardly, and

moreover, air is more fully excluded from between the strips, and to this advantageous arrangement the improved corner piece or strip 7 is added to complete the tight or weather-excluding joints. It will be understood that the strips 5 and the pieces 7 may all be varied in their dimensions to adapt the same to different applications without departing from the spirit of the invention. It is also proposed to apply coloring matter 75 to the strips 5 and pieces 7 and ornament the surfaces thereof to represent stone or give a pebble-dash effect, and in some instances comminuted stone will be adhesively applied to the outer surfaces of the strips 80 with advantageous ornamental effect and pleasing design when the strips are applied in overlapped relation as hereinbefore specified and shown in the drawings.

One of the most advantageous applications of the improved siding strip and corner piece is for covering weather-worn and rotted side walls of old buildings to provide a new surface instead of patching the old siding and painting the same as is now commonly practiced. The cost of applying the improved siding with the special form of corner piece over an old surface as just explained will not be any greater than that required for fixing or repairing the old surface or side wall covering, and in fact the application of the improved siding with the corner pieces will materially add to the durability of an old building and give it a practically new appearance and at the same time tighten up and close the old building wall and render the latter much warmer.

What is claimed as new is:

1. A covering for the side wall of a building, consisting of main strips of equal width throughout their lengths having transverse slots extending therethrough from one edge of each and partially across the width of each strip, the strips being intended for overlapping association to simulate brick appearance, and a reversible corner piece for application to both inner and outer corners, the said piece having at one side edge a central maximum projection and the adjacent edge portions inclining upwardly towards the ends of the corner piece and the opposite side edge having a central maximum depression with the adjacent edge portions inclining upwardly to the ends of the piece, the end edges of the piece having central substantially rectangular projections and reversely inclining side edge portions extending from the opposite ends of the central projections to the side edges.

2. A corner piece for application to cover strips for a side wall, consisting of a normally flat plate with one side edge having a central maximum projection from which the adjacent side edge portions have an upward inclination to the ends of the piece and the

opposite side edge having a maximum depression with the adjacent edge portions extending upwardly towards the end, the piece also having end edges with central substantially rectangular projections and the remaining portions of the said end edges inclining outwardly in reverse directions to and forming corner structures with the terminals of the said side edges, the corner

piece being centrally bendable in reverse directions in line with the maximum projection and depression at the opposite side edges to adapt the same to inner and outer corner formations.

In testimony whereof I have hereunto set my hand.

PETER P. WELTY.
